United States Patent Office

Des. 203,726
Patented Feb. 8, 1966

203,726

HANGER

Vito Tobia, 236 Montrose Ave., Brooklyn, N.Y.

Filed Nov. 27, 1964, Ser. No. 82,802

Term of patent 14 years

(Cl. D80—8)

FIG. 1

FIG. 2

FIG. 4

FIG. 3

FIG. 5

FIG. 1 is a front perspective view of the hanger showing my new design;

FIG. 2 is a perspective view taken from the right side thereof;

FIG. 3 is a perspective view taken from the rear and left side thereof;

FIG. 4 is a bottom plan view thereof; and

FIG. 5 is a top plan view thereof.

The dominant features of my design reside in the portions shown in full lines.

I claim:

The ornamental design for a hanger, as shown and described.
